SHEET FEEDING MECHANISM

George G. Hyde, Darien, Conn., and John H. Hochuli, Woodhaven, N. Y., assignors to Crucible Steel Company of America, New York, N. Y., a corporation of New Jersey

Application December 23, 1944, Serial No. 569,586

6 Claims. (Cl. 271—10)

1

The invention relates to a feeding mechanism capable of handling heavy metal sheets as produced in steel mills, which are of large size and weight, frequently being about 12 ft. long, nearly 3 ft. wide, and weighing about 400 lbs. or upwards. The mechanism is especially useful where sheets of the above character are deposited from time to time upon a supporting frame in quantities as needed to maintain a pack of sheets on the frame, and the sheets are required to be separated successively from the pack of sheets on the frames, and fed to a traveling conveyor or other receiving structure.

The invention aims to provide such a mechanism wherein the supply of sheets on the frame may be added to as needed from time to time, without interfering with the continuity of the feeding operations. Special difficulties are involved in securing this advantage in a mechanism handling heavy sheets as above referred to, because of the weight or bulk of the sheets, and prior mechanisms used for this class of material have required that the feed be interrupted while the supply of sheets to be fed was being replenished.

Another object of the invention is to provide a feeding mechanism of the above character wherein the sheet or sheets being separated from the pack will be largely relieved during the separating step from the weight of the remaining sheets of the pack, thus reducing markedly the force required to move the sheet being separated and minimizing marring of adjacent sheet surfaces due to excessive friction and rubbing of one against the other during the separating movement.

The invention also aims to provide a feeding mechanism of the above nature which will afford facile and reliable delivery of the sheet or sheets to be delivered after being moved relative to the pack of sheets as above described; and to provide such a mechanism which will handle sheets of various sizes without requiring special adjustments to accommodate the machine thereto. Further objects and advantages of the invention will be in part obvious and in part specifically referred to in the description hereinafter contained which, taken in conjunction with the accompanying drawings, discloses a mechanism of preferred construction which is capable of operating in accordance with the invention; however the disclosure should be regarded as merely illustrative of the principles of the invention in its broader aspects. In the drawings—

Fig. 1 is a vertical sectional view taken through

2

a feeding mechanism constructed to operate in accordance with the invention; the section being taken on line 1—1 of Fig. 2, looking in the direction of the arrows.

5 Figs. 2 and 3 are respectively a general plan view and front elevation of the machine shown in Fig. 1.

Fig. 4 is an enlarged front elevation showing certain operating parts of the machine.

10 Figs. 5 and 6 are detail sections taken respectively on the line 5—5 and 6—6 of Fig. 4 looking in the direction of the arrows.

Fig. 7 is a section on the line 7—7 of Fig. 6 looking in the direction of the arrows.

15 Fig. 8 is a schematic view showing certain fluid pressure control lines which may be used in connection with the mechanism.

20 In accordance with the present invention a pack of sheets to be fed is deposited on a frame of such construction that the sheets of the pack stand up edgewise on the frame, and the pack is slideable along the frame to a position in which its forward sheet comes up against a stop. Thereupon a periodically operated ejector engages the end sheet or sheets to be fed, and moves

25 the latter upwardly in a direction parallel to the pack until the ejected sheet is free of engagement with the stop member and so positioned that it may swing downwardly away from the pack to a conveyor or like point of delivery. Preferably a pusher is employed which is operated alternately with respect to the ejector, to advance the pack into engagement with the stop after each successive sheet has been ejected from the pack, and we also prefer to employ a cradle which acts automatically to receive and cushion

30 the fall of the ejected sheets during their downward swinging movement above referred to and deposit them accurately upon a conveyor or other delivery apparatus used in connection with the mechanism. The mechanism also is preferably so constructed that gravity effects or largely assists in effecting the swinging movements of the ejected sheets and cradle. The above and 35 other features of the invention will be more apparent as the description proceeds.

Referring first more particularly to Figs. 1 and 2, the illustrated form of the invention is shown as having a supporting frame of the character 40 above mentioned, which consists of a plurality of parallel rails 1 mounted upon a bedplate 2, in such manner that a pack 3 of steel sheets to be fed may be maintained upon the rails 1 with the sheets standing up on edge, and their bottom edges resting on the rails so that the pack may

55

be pushed up against a transverse stop 4 extending across the forward ends of the rails. The supply of sheets in the pack 3 will be added to from time to time as successive sheets are fed, usually by an overhead crane which deposits further sheets from time to time on the rails behind the pack, thus adding sheets thereto as needed to maintain a continuous supply. We prefer to provide an appropriate number of mechanical pushers 5 which are operated periodically to push the stack forwardly until its forward sheet engages properly against stop 4. As shown each pusher 5 is in the form of a plunger operated by a pneumatic cylinder 6 as will be later referred to in more detail. The stop 4 is shown as provided with a bottom ledge 7 which runs across the frame underneath the forward ends of rails 1.

An appropriate number of sheet ejector members are provided which are moved periodically into engagement with the sheet 3a of the pack which is in engagement with the stop 4, to raise the sheet 3a to the position indicated at the top of Fig. 1. These ejector members may be all constructed alike, so a description of one will serve for all. In the illustrated form of the invention each ejector member takes the form of a reciprocable rod 8 of T-shaped cross section, which is slidably supported within the stop member 4 by means of guide plates 9 (see Figs. 4 and 5) and is actuated by an appropriate cam mechanism carried by a bracket 10 fastened to the bottom ledge 7 of stop member 4. In the form shown, each bracket 10 is located somewhat to one side of its corresponding ejector rod 8, and the lower end of the rod is attached to a cam follower having side plates 11 (Fig. 4) between which are mounted upper and lower rolls 12 and 13 respectively, the follower being guided by a roll 14 (Fig. 3) which is mounted on a stud 16 extending from one of the plates 11, and working in a slot 15a in bracket 10. A cam 16 carried by a rotatable shaft 17 works between the rollers 12 and 13 and thus all of the ejector rods are reciprocated in unison in paths parallel to the plane of stop member 4 and the sheets 3.

When the ejector rods 8 are in lower retracted position their lower ends underlie the bottom edge of the forward sheet of the pack which is in engagement with the stop member. If the sheets are to be ejected one at a time the sheet engaging portion of the ejector rod will be of effective thickness somewhat less than the thickness of one sheet, or if it is desired to eject more than one sheet simultaneously the upper end or nose of the ejector member will be made correspondingly larger. To facilitate the upward ejecting motion of the plate, the stop member 4 is preferably provided with a suitable number of anti-friction rollers 18 (Figs. 5 and 6) which project slightly beyond the plane of the adjacent surface of the stop member, and thus relieve the friction between the sheet being ejected and member 4. As shown each of these roller members is journaled in a housing 19 clamped to the outer side of stop member 4 and projecting into a hole 20 therein.

It should be noted that due to the upstanding position of the sheets in pack 3, the sheet being ejected is largely relieved from excessive pressure against or frictional engagement with the face of the adjacent stationary sheet of the pack, which is of special importance in the handling of sheets weighing hundreds of pounds apiece as is the case with steel sheets of customary sizes used. Thus the power required to eject the sheets

is greatly reduced, and also marring of the sheet surfaces, and sheets adjacent the ones being displaced are not moved by frictional engagement therewith. While a sheet is being ejected, the pusher members 5 are preferably relieved of any substantial pressure against the pack for similar reasons, as hereinafter described in more detail. The pushers need be operated only intermittently between ejecting operations, to push the pack forwardly until the next sheet or sheets to be ejected are in proper position adjacent to stop 4. Also when further sheets are to be added to the pack 3, the pushers 5 will be operated to move them to proper position parallel to and in contact with the adjacent sheets of the pack. It will be noted that a construction of the above described type affords facile addition of more sheets to the pack whenever desired, without interfering with the ejecting operations.

When the sheet to be ejected has been pushed up by ejector members 8 to the position indicated for the sheet 3a at the top of Fig. 1, this movement frees the lower portion of the sheet 3a from engagement with the stop member 4, the lower edge of the sheet 3a being then at about the level of the forwardly extending ledge 4a (Fig. 7) at the top of stop member 4. At this stage the sheet 3a is free to swing downwardly away from the pack of sheets 3 about its lower edge as a pivot, as indicated by the arrow 3b in Fig. 1. To facilitate this downward movement we prefer to position the rails 1 and the stop member 4 in such manner that the pack of sheets 3 and the ejected sheet 3a will assume a somewhat forwardly inclined position. As shown in Fig. 1 the rails 2 are inclined about 7° to the horizontal and the stop member 4 about 7° to the vertical, which will usually be sufficient to cause the above mentioned downwardly swinging movement of the sheet 3a to be initiated by the action of gravity. This downward inclination of the rails 1 also facilitates the movement of the pack of sheets along the rails into engagement with stop 4, and need not be so great as to largely impose the weight of the pack on the forward sheets and thereby produce excessive friction of the sheet or sheets being ejected against the face of the adjacent stationary sheet of the pack.

One or more mechanically actuated sheet tilting members may be used and operated in timed relation to the ejector members 8 to positively initiate the tilting movement of the sheet 3a, when the latter has reached the position indicated at the top of Fig. 1. As shown schematically in Fig. 1, these sheet tilting members comprise rotary arms 21 carried by a shaft 22 which is rotated in timed relation to shaft 17 previously mentioned.

As the sheet 3a is moved upwardly while being ejected from the pack, a gap is created between stop 4 and the remainder of the pack. To prevent the ejected sheet 3a from slipping back into this gap when the ejector rods 8 move downwardly, suitable latching or locking devices may be employed in appropriate number spaced along the stop member 4. As shown in Fig. 7 such locking devices may each consist of a dog 32 pivotally mounted on a stud 33 which extends across a recess 34 in the face of stop member 4, the dog being urged by a spring 35 toward a position wherein its upper end 36 projects out beyond the adjacent face of stop member 4. Thus while the above gap exists, the above locking members prevent the ejected sheet from slipping downwardly into the gap, but when the pack of sheets is again

pushed up against stop 4 after the ejecting operation has been completed, the upper ends 36 of the dog 32 are pushed into their corresponding recesses 34 against the action of the springs 35.

Preferably the mechanism includes a cradle which receives and underlies each ejected sheet as the latter swings downwardly, and moves downwardly therewith to ease the fall of the sheet and deposit the latter accurately onto a conveyor or other delivery apparatus. In the illustrated form of the invention, this cradle comprises a plurality of swinging arms 23 which are fixed at their lower ends to a spindle 24 running across the machine underneath the ledge 4a and journaled in brackets 25 (Fig. 3). The arms 23 are urged toward the upper position shown in Fig. 1 by appropriate means such as one or more counterweights 26 carried by arms 27 (Fig. 1) fastened to the shaft 24. Thus when the sheet or sheets 3a have been ejected from the pack to the upper position indicated at the top of Fig. 1, the cradle constituted by the arms 23 lies against the adjacent face of the sheet 3a, and as the ejected sheet swings downwardly as above described, the cradle partially sustains the weight of the sheet and checks the fall of the latter, until the sheet is deposited at its point of delivery. In the form shown a delivery conveyor is provided, having freely rotatable rollers 28 journaled in side plates 29, the conveyor being downwardly inclined so that as the ejected sheets are successively deposited upon it by the arms 23, the sheets pass downwardly by gravity along the conveyor and are finally delivered to appropriate apparatus such as the traveling conveyor indicated schematically at the right of Fig. 1 as having rollers 30 supported in side plates 31. After the sheet has moved along the above mentioned downwardly inclined conveyor to a point where it is clear of the arms 23, the cradle swings up by gravity to the position indicated in Fig. 1, where it is ready to receive the next sheet ejected from the pack.

It should be noted that a feeding mechanism of the above type requires no adjustments to accommodate itself to sheets of different lengths or widths. The lifting movement produced by the ejector members may be the same for different widths of sheet and will usually be much less for widths of the narrowest sheets operated upon. The remaining movements of the sheets after they have been raised to upper position may be produced entirely by gravity until the sheets reach the traveling conveyor above mentioned.

The rate of feed may also be readily adjusted to conform to requirements, the mechanism being capable of rapid operation, and adjustment of the rate of feed requiring merely regulation of the speed of rotation of shaft 17. The mechanism may be readily adapted to handle longer sheets merely by adding further ejector units.

In Fig. 8 we have shown schematically a pneumatic pressure operating system for the cylinder 6 and plunger 5, according to which air under relatively high pressure is supplied from a pipe line 36, and air under low pressure through a pipe 37. At stages where the ejector members 8 are in lower inactive position, a valve 38 controlled by a cam 39, opens to admit air under high pressure into the rear end of cylinder 6, thus causing the plunger 5 to push the pack of sheets forward into position against stop member 4. Then a valve 40 controlled by a cam 41, opens for a brief period to relieve the relatively high pressure in the pipe 42 which leads to the outer end

of cylinder 6. A check valve 43 interposed between the pipes 37 and 42 and actuated by a cam 44, closes off the supply of low pressure air while valve 38 is open, but after valves 38 and 40 have closed, air under low pressure is maintained in the outer end of cylinder 6, thus imposing through plunger 5 a relatively low pressure on the pack of sheets, which pressure need be merely sufficient to hold the sheets of the pack in proper relation to each other until the high pressure air is again applied after the completion of the sheet ejecting step. A valve 44 may be used to vent the cylinder 6 when pusher 5 is to be retracted to admit further sheets to the pack.

While the invention has been disclosed as carried out by a mechanism of the above described specific construction, it should be understood that changes may be made therein without departing from the invention in its broader aspects, within the scope of the appended claims.

We claim:

1. A sheet feeding mechanism of the class described including a supporting frame constructed to underlie the bottom edges of a pack of upstanding metal sheets and afford sliding movement of such pack along the frame, a stop member limiting the aforesaid sliding movements of such pack, a sheet ejector member having means for periodically actuating the same to raise a sheet of the pack from stop engaging position to an upper position wherein said sheet is free to swing downwardly, said mechanism including structure whereby said sheet is caused to swing downwardly to a discharged position after being moved by the ejector member to the above mentioned upper position, said mechanism also including a cradle mounted for movement between upper and lower positions wherein it receives said sheet during the aforesaid downward swinging movement of the latter and moves downward therewith.

2. A sheet feeding mechanism of the class described including a supporting frame constructed to underlie the bottom edges of a pack of upstanding metal sheets and afford sliding movement of such pack along the frame, a stop member limiting the aforesaid sliding movements of such pack, a sheet ejector member having means for periodically actuating the same to raise a sheet of the pack from stop engaging position to an upper position wherein said sheet is free to swing downwardly, said mechanism including structure whereby said sheet is caused to swing downwardly to a discharged position after being moved by the ejector member to the above mentioned upper position, said mechanism also including a cradle mounted for movement between upper and lower positions wherein it receives said sheet during the aforesaid downward swinging movement of the latter and moves downward therewith, and a conveyor positioned to receive sheets moving downwardly with the cradle as aforesaid.

3. A sheet feeding mechanism of the class described including a supporting frame constructed to underlie the bottom edges of a pack of upstanding sheets and afford sliding movement of such pack along the frame, a stop member limiting the aforesaid sliding movements of such pack, said frame being somewhat downwardly inclined in a direction towards said stop member to cause the sheets of the pack to lie obliquely on the frame, and a sheet ejector member having means for periodically actuating the same to raise a sheet of the pack from stop engaging position to

an upper oblique position wherein said sheet is free to swing downwardly by gravity from its upper oblique position aforesaid, said mechanism also including a cradle mounted for movement between upper and lower positions wherein it receives said sheet during the aforesaid downwardly swinging movement of the latter and moves downwardly therewith, said cradle being urged toward its upper position but having structure whereby it moves downwardly as aforesaid under the weight of the downwardly swinging sheet.

4. A sheet feeding mechanism of the class described including a supporting frame constructed to underlie the bottom edges of a pack of upstanding metal sheets and afford sliding movement of such pack along the frame, a stop member limiting the aforesaid sliding movements of such pack, a sheet ejector member having means for periodically actuating the same to engage the underside of the end metal sheet abutting said stop member to raise said sheet of the pack from stop engaging position to an upper position free of said stop member, said mechanism including latching means operative to prevent the sheet from slipping back into position between the pack and the stop after being raised to the aforesaid upper position.

5. A sheet feeding mechanism of the class de-

scribed including a supporting frame constructed to underlie the bottom edges of a pack of upstanding metal sheets and afford sliding movement of such pack along the frame, a stop member limiting the aforesaid sliding movements of such pack, said stop member being positioned to engage the lower portion of the adjacent sheet of the pack, and a cradle pivoted about a horizontal axis, and urged toward a position above the level of the stop member, a sheet ejector member having means for periodically actuating the same to raise a sheet of the pack from stop engaging position to an upper position wherein said sheet is free of said stop member, and adjacent said cradle, whereby a sheet pushed up to said last mentioned position may swing downwardly in a direction away from the pack while resting against said cradle.

6. The combination of claim 5 wherein said cradle is urged by gravity toward a position above the level of the stop member, and tilted to a lower position by the weight of the sheet engaging the cradle, and an inclined conveyor positioned to receive sheets from said cradle after the latter is tilted to a lower position as aforesaid.

GEORGE G. HYDE.
JOHN H. HOCHULI.
